UNITED STATES PATENT OFFICE.

ERASMIUS COLLINS QUINBY, OF LOS ANGELES, CALIFORNIA.

DESIGN FOR A CANDY-BOX.

55,643.

Specification for Design.

Patented July 6, 1920.

Application filed February 16, 1920. Serial No. 359,183. Term of patent 14 years.

To all whom it may concern:

Be it known that I, ERASMIUS COLLINS QUINBY, a citizen of the United States, residing at 506 South St. Andrews street, in the city of Los Angeles, in the county of Los Angeles and State of California, have invented a new, original, and ornamental Design for Candy-Boxes, of which the following is a specification, reference being

had to the accompanying drawing, forming part thereof.

The figure is a perspective view of a candy box showing my new design.

I claim:

The ornamental design for a candy box, as shown.

ERASMIUS COLLINS QUINBY.
